(57) **CLAIM**

The ornamental design for a narrow card file cabinet, as shown and described.

DESCRIPTION

FIG. 1 is a front perspective view, a right perspective view and a top perspective view of a narrow card file cabinet, showing the first embodiment of my new design;

FIG. 2 is a rear perspective view, a left perspective view, and a top perspective view thereof;

FIG. 3 is a front elevational view thereof;

FIG. 4 is a rear elevational view thereof;

FIG. 5 is a left side view, the right side view being a mirror image of FIG. 5;

FIG. 6 is a top plan view thereof;

FIG. 7 is a partial enlarged view of FIG. 1;

FIG. 8 is a partial enlarged view of FIG. 1;

FIG. 9 is a front perspective view, right perspective view and top perspective view of a narrow card file cabinet, showing the second embodiment of my new design;

FIG. 10 is a rear perspective view, a left perspective view, and a top perspective view thereof;

FIG. 11 is a front elevational view thereof;

FIG. 12 is a rear elevational view thereof;

FIG. 13 is a left side view, the right side view being a mirror image of FIG. 13;

FIG. 14 is a top plan view thereof;

FIG. 15 is a partial enlarged view of FIG. 9;

FIG. 16 is a partial enlarged view of FIG. 9;

FIG. 17 is a front perspective view, right perspective view and top perspective view of a narrow card file cabinet, showing the third embodiment of my new design;

FIG. 18 is a rear perspective view, a left perspective view, and a top perspective view thereof;

FIG. 19 is a front elevational view thereof;

FIG. 20 is a rear elevational view thereof;

FIG. 21 is a left side view, the right side view being a mirror image of FIG. 21;

FIG. 22 is a top plan view thereof;

FIG. 23 is a partial enlarged view of FIG. 17; and,

FIG. 24 is a partial enlarged view of FIG. 17.

The broken lines in the figures are for the purposes of illustrating portions of the narrow card file cabinet, which form no part of the claimed design.

The dash-dot-dash lines are for an notating enlarged views, which form no part of the claim design.

1 Claim, 21 Drawing Sheets
